UNITED STATES PATENT OFFICE.

CONVERSE W. LLOYD, OF CHICAGO, ILLINOIS, ASSIGNOR TO THE SANI-FOLD COMPANY OF CALIFORNIA, A CORPORATION OF CALIFORNIA.

FOLDING TOOTHBRUSH.

• 1,345,939.

Specification of Letters Patent.

Patented July 6, 1920.

Application filed August 3, 1916. Serial No. 112,977.

To all whom it may concern:

Be it known that I, CONVERSE W. LLOYD, a citizen of the United States, and a resident of the city of Chicago, in the county of Cook and State of Illinois, have invented certain new and useful Improvements in Folding Toothbrushes; and I do hereby declare that the following is a full, clear, and exact description of the same, reference being had to the accompanying drawings, and to the numerals of reference marked thereon, which form a part of this specification.

This invention relates to an improved form of sanitary folding tooth brush in which consideration has been given to every possible detail, insuring the utmost cleanliness and simplicity of construction, so that when folded into position out of use the brush is entirely protected with the bristles out of contact with the walls of the container or shield, and yet with an opening there-around sufficient to permit ventilation.

It is an object of this invention to construct a sanitary folding tooth brush embracing a hinged handle, which, at one end, is provided with a container adapted to receive the brush folded therein with the brush head engaging in a notch or groove to insure spacing of the bristles of the brush from the walls of the container at all points.

It is also an important object of this invention to construct a sanitary folding tooth brush, the handle of which is hinged and provided with a container adapted to receive the brush folded therein, and with one wall of said container notched to engage the brush head, spacing the bristles of the brush from the walls in the container, and further so positioning the brush head as to insure a small opening entirely around the same between the brush head and the upper walls of the container to permit ventilation of said container and brush.

It is furthermore an object of this invention to construct a tooth brush the handle of which is jointed and provided with a container adapted to receive the brush folded therewith and out of contact therewith, wherein the container is unitary with a section of said brush handle, and smoothly rounded at all points to permit easy cleaning thereof, and preventing accumulation of any foreign matter therein.

It is finally an object of this invention to construct a compact, self draining, folding

sanitary tooth brush wherein the brush head is adapted to fold into a suitable container formed integral with a section of the handle, the device when folded affording an eye at the hinge joint by which the device may be readily hung up when out of use.

The invention (in a preferred form) is illustrated in the drawings and hereinafter more fully described.

In the drawings:

Figure 1 is a side elevation of a device embodying the principles of my invention, with parts in section and showing the device in extended position ready for use.

Fig. 2 is a top plan view of the device shown in Fig. 1.

Fig. 3 illustrates the device folded, and in the self-draining position assumed when hung up out of use.

Fig. 4 is a view partly broken away and shown in section, illustrating the device in folded position.

Fig. 5 is a detail section taken on line 5—5 of Fig. 4.

Fig. 6 is a detail section taken on line 6—6 of Fig. 4.

Fig. 7, is a view partly broken away and shown in section, illustrating a modified form of the device in folded position.

Fig. 8, is a section taken on line 8—8, of Fig. 7.

Fig. 9, is a section taken on line 9—9, of Fig. 7.

As shown in the drawings:

The brush is made up of two handle sections 1 and 2, preferably constructed of ivory, bone, celluloid or any other noncorrosive material, said sections being hingedly connected to one another by means of a knee-joint 3. The section 1, has formed integral therewith a brush head 4, in which a number of bristles 5, are secured in a unusual manner, and an elongated cup shaped container 6, is integrally connected at the middle point of one of its ends with the handle section 2, and, as clearly shown, is smoothly rounded at all points to prevent accumulation of foreign matter therein, and to facilitate cleaning thereof. The upper part of the connecting shank 7, between the container 6, and handle section 2, is provided with a groove or notch 8, which is of a size to receive the handle section 1, snugly therein when the device is in the folded position shown in Figs. 3 and 4. When the device is in the

folded position as shown in Fig. 3, the eye afforded by the handle sections 1 and 2, permits the insertion therethrough of a nail or hook on which the brush may be hung when 5 out of use.

The rounded interior and exterior of the container 6, prevents the collection of any particles of dirt, dust, or tooth paste therein, and said container is of a size sufficient to 10 insure spacing of the bristles 5, from the walls thereof at all points. The notch 8, into which the handle section 1, fits snugly, serves to center the brush head 4, so that the bristles 5, are properly disposed within the 15 container and out of contact therewith. A small gap or opening is afforded entirely around the centered brush head 4, at the upper end of the container, so that a free circulation of air is permitted, providing 20 proper ventilation for the container, and yet said opening is of such a size as to prevent flies or like insects from finding access therethrough, particularly when the device is hung up out of use.

25 It will be observed that the groove or notch 8 in serving to prevent lateral displacement of the brush end of the device when folded also serves to maintain the said brush end in proper position to provide the 30 small gap or opening entirely around said brush head.

This method of ventilation is greatly superior to those devices in which the container is provided with a number of apertures in its bottom or side walls, for the 35 reason that apertures afford a ready place for the lodgment of dirt or other matter. The slope of the inner walls of the container 6, is such that when the device is 40 hung up, as shown in Fig. 3, it will drain freely, but ordinarily the means of ventilation provided is sufficient to allow the bristles to dry by evaporation.

In the modified form of the device shown 45 in Figs. 7, 8 and 9, the brush consists of handle sections 9 and 10, hingedly connected together by a knee-joint 11. The section 9, has integrally formed thereon a brush head 12, in which suitable bristles 13, are mounted. An elongated cup shaped container 14,

is integrally connected at the middle point of one of its ends with the handle section 10, and is smoothly rounded at all points to facilitate cleaning and prevent the accumulation of foreign matter therein. Said brush 55 head 12, has its outer end and its sides slightly tapered downwardly and is of a size to permit the same to contact and closely fit into the upper or open end of the container 14. To permit the container 14, to 60 be properly ventilated and the bristles 13, to dry out when the tooth brush is in closed position a passage, opening or groove 15, is cut or formed in the container and handle section 10, affording a communication 65 between the interior of the container 14, and the eye or opening afforded by the handle sections 9 and 10, when the brush is closed, and ready to be hung up.

I am aware that the details of constructions may be varied through a wide range without departing from the principles of this invention, and I therefore do not purpose limiting the patent granted otherwise than necessitated by the prior art. 70

75 I claim as my invention:

In a folding tooth brush, handle sections hingedly connected to one another, a brush on one of said sections, a container on the other section adapted to receive the brush 80 folded thereinto with the bristles of the brush concealed and spaced from the walls of the container at all points, said container handle section having a groove therein adapted when the sections are folded to receive the brush section intermediate its 85 length to insure centering of said brush when folded into said container, said brush and container being so constructed as to afford a continuous opening around the brush 90 at the upper end of the container when the brush is folded thereinto.

In testimony whereof I have hereunto 95 subscribed my name in the presence of two subscribing witnesses.

CONVERSE W. LLOYD.
